CLAIM

The ornamental design for a water bottle for bicycle, as shown and described.

DESCRIPTION

FIG. 1 is a top plan view of a water bottle for bicycle showing my new design;

FIG. 2 is a side elevation view thereof;

FIG. 3 is a bottom plan view thereof;

FIG. 4 is a front elevation view thereof;

FIG. 5 is a rear elevation view thereof; it being understood that the broken lines are for illustrative purposes only and form no part of the claimed design; and

FIG. 6 is an opposite side elevation view of FIG. 2.
